UNITED STATES PATENT OFFICE.

JOHN T. ALLMAND, OF DETROIT, MICHIGAN, ASSIGNEE TO TERNSTEDT MANUFACTURING CO., OF DETROIT, MICHIGAN, A CORPORATION OF MICHIGAN.

WINDOW-STEADYING DEVICE.

1,287,606.

Specification of Letters Patent. Patented Dec. 17, 1918.

Application filed February 2, 1918. Serial No. 215,013.

To all whom it may concern:

Be it known that I, JOHN T. ALLMAND, a citizen of the United States, residing at Detroit, in the county of Wayne, State of Michigan, have invented a new and useful Improvement in Window-Steadying Devices, of which the following is a specification.

This invention relates to automobile carriage window construction. In the better types of present day closed bodies for automobiles some provision is made for keeping the window either completely closed or partly open. A simple arrangement for this purpose is the familiar strap which can be clamped to hold it in various positions. A more expensive and more desirable arrangement is the window lifting device such as roughly illustrated in Figure 1 and which 10 is operated by a crank handle on the inside of the body. In a well built job the window is substantially rattle-proof in either the down or the up position for the window guide walls converge at top and bottom and 15 the header is made so as to fit it tightly in the closed position. In most of the intermediate positions, however, the common rubber rollers or other devices that are now 20 quite generally used as anti-rattling devices in a window of this kind do not jam the window absolutely tight against the side of the groove for the reason that they must 25 be spaced for the farthest position the sash reaches inward in descending or rising. 30 Consequently the window cannot be held absolutely tight from lateral vibration under the present methods of construction.

It is to provide a device to make the window absolutely rattle-proof when partially raised that this invention is directed. It performs the additional function, however, of making the window rattle-tight in case it has not been fitted in the way it should be when it is closed. These results 40 and the structure to accomplish them will more fully appear in the more detailed description.

In the drawings,—

Fig. 1 is a vertical section of the side 50 of a closed automobile body.

Fig. 2 is an enlarged vertical section of the window-steadying device.

Fig. 3 is a front elevation of the device.

Figs. 4 and 5 are enlarged longitudinal 55 and cross sections respectively.

a is the ordinary window frame provided with the ordinary window-way or groove *b*. *c* is the fence and *d* the fence engaging clip now in common use. *e* represents the chain lift operated by a crank *f* to raise and lower 60 the window and lock the window in raised and lowered position. This is already part of the prior art. The front wall *g* of the window-way which inclines outward from top to sill constitutes a jamb against which 65 the felted-window sash *h* is held when the window is in raised position by the felted header construction *i* and the fence *c*.

It will be noticed that the sash in passing up by the roller *j* varies as regards the distance from the inside of the sash to the outside wall of the way. In the construction shown this is due primarily to the inclination of the outer wall of the way. This inclination is almost a universal construction 75 with windows which lift over a fence. This variation of the distance from the inside of the sash to the outside wall of the window way will occur in any window construction in which the window sash is at an angle 80 with respect to the outside wall of the way. This occurs in the construction shown in the drawings by reason of the outer wall of the window way being inclined to the vertical.

Obviously there is considerable difference 85 in the distance from the inside of the sash to the outside wall of the way at any given point. Consequently the anti-rattler devices that have heretofore been employed for this purpose have usually been placed at a position 90 calculated to accommodate the sash when in that position, where the distance from the inside of the sash to the outside wall of the way is maximum. Hence such anti-rattler devices do practically no good 95 when the window is partially raised for then they cease to function. I have designed an anti-rattler capable of accommodating itself to the differential positions of the window and yet not bear with such tenacity against 100 the sash when the maximum pressure is exerted as to hamper the raising and lowering of the window.

The roller *j*, preferably made of "bake-lite" or rubber, instead of being stationary, 105 has movable journals made possible by the saddle *k*, which slides in and out on the pins *m*, which are connected at their inner ends by the bar *n* and which at their outer ends are riveted to the housing *p*. This housing 110

p can be screwed to the window frame molding by screws on the front and side of the molding. The coil springs *q* tend to project the saddle and the roller outward so as to 5 press the sash bar against the wall of the window-way.

It will be seen that the roller *j* will accommodate itself to the sash regardless of the widening of the distance from the inside of the sash to the outside wall of the way as the window is raised past the roller.

- 10 The roller having theoretically only a line contact with the window no matter how great the pressure upon the roller, and of course the roller revolving upon an axis, lessens the friction when the sash is raised or lowered. The anti-rattler, therefore, reduces to a minimum the hindrance to the raising and lowering of the sash while at 15 the same time it is adapted to follow the sash regardless of its differential positions and insure a pressure against the sash which will hold it against the outside wall of the way and prevent rattling.
- 20

25 What I claim is:

1. In a carriage construction, the combination of a pair of window-ways having their outer walls inclined from the vertical, a sash which in raising or lowering is tipped 30 against the outer walls of the ways so that the distance between the inside of the sash and the outside wall of the way varies at any given point as the sash travels by such point, and a pressure device for keeping the

sash against the outside wall of the way, the 35 said pressure device supported to the inside of the sash and comprising an anti-friction roller carried upon a yieldable support whereby the pressure device may accommodate itself to different positions of the window without unduly hampering the travel 40 of the window.

2. In a carriage construction, the combination of a pair of window ways, the molding on the inside wall of the way being cut 45 away, a sash which when raising or lowering is tipped toward the outer wall of the ways so that the distance of the inside of the sash and the outside of the ways varies as the sash travels by the cut-away portion of the said 50 molding, and a pressure device for keeping the sash against the outside wall of the way regardless of the varying distance from the inside sash to the outside wall of the way, the said pressure device comprising an angle 55 plate housing adapted to be fastened to the molding adjacent the cut-away portion and to cover said cut-away portion, guides supported by said angle plate housing, a saddle 60 slidable on the guides, a roller journaled in the saddle and adapted to make contact with the inside of the sash, and spring means for normally keeping the roller projected outwardly through a slot in the angle plate housing.

In witness whereof, I have hereunto set my hand on the 24th day of January, 1918.

JOHN T. ALLMAND.
